OAT HULLER

Application filed January 8, 1929. Serial No. 331,075.

The object of our invention is to provide an oat huller of simple, durable and inexpensive construction, which is reliable and positive in its operation.

5 A further object is to provide an oat huller having simple and rigid means for hulling the oats, which is rapid in its operation and at the same time adapted to perform its work without clogging or tangling.

10 Our invention consists in the construction, arrangement and combination of the various parts of the device, whereby the objects contemplated are attained, as hereinafter more fully set forth, pointed out in our claims, 15 and illustrated in the accompanying drawings, in which:

Figure 1 is a longitudinal sectional view of our improved oat huller,

20 Figure 2 is a transverse sectional view taken on the line 2—2 of Figure 1,

Figure 3 is a front view of the rotating huller element,

Figure 4 is an end elevation of same.

25 The numeral 10 indicates a cylindrical casing, one end of which communicates with a separating device, such as ordinarily used in oat hullers and which forms no part of our present invention. The other end of the casing 10 is provided with a wall 11 having a central opening provided with an inwardly projecting collar 12. Said collar is connected to the lower end of a hopper 13. One side of the hopper 13 is provided with a bearing 14 for rotatively receiving a shaft 15 located centrally and longitudinally within the collar 12, and has its outer end provided with a driving pulley 16.

30 The inner end of the shaft 15 is designed to support the huller element 17 which comprises a disk 18 supported by a hub 19, said hub being rigidly secured to the shaft 15.

35 The periphery of the disk 18 has a series of outwardly extending and radial blades 20 mounted in planes parallel with the shaft 15. The front edges of the inner ends of the blades 20 are connected by means of an annular blade 21 which strengthens and supports the blades 20. The forward edges of 40 the blades 20 are bent to form flanges 22, said

flanges extending in a direction of the rotation of the huller element.

The back edge of each of the blades 20 is provided with a segmental plate 23. The advancing edges of said plates are bent forwardly to engage the forward edge of the back face of the adjacent plate 23, so that the peripheral edges of the plates 23 are of helical formation, so that grain engaged by the peripheral edges of said plates will be thrown 55 rearwardly in the casing.

The outer end of the back edge of each of the blades 20 is provided with rearwardly projecting flange 24, having its lower edge provided with a circumferential projection 60 25 extending in the direction of rotation of the huller element. The impeller is mounted on the shaft 15 in such a manner that the collar 12 enters the plate 21 and terminates between the plate 18 and the said collar.

65 By this arrangement it will be seen that if the hopper 13 is filled with oats or similar grain to be hulled, and the shaft 15 is rapidly rotated, then the huller element will also be rotated in a counterclockwise direction, as 70 viewed in Figure 2, then oats will be delivered through the collar 12 and will fall downwardly into the path of the rotating blades 20, and the oats engaged by said blades before it has reached the bottom of the casing 10. 75

The velocity of the blades 20 is such that a large per cent of the grain will be hulled by the impact between said grain and said blades. The kernels and hulls and the un-hulled grain will be delivered outwardly to 80 the sides of the casing 10 by centrifugal force and will engage said casing with a considerable force which will hull the grain not previously hulled. A large portion of the grain will rebound and be delivered toward the

85 center of the huller element, and be engaged by the front surface of the members 24. The members 25 strengthen the members 24, as well as prevent the grain from moving inwardly too rapidly, which will again be 90 thrown outwardly over the peripheral edges of the members 24 and be engaged by a preceding blade 24.

95 The back surface of the helical plates 23 assist in advancing the material longitudi- 100

nally within the casing 10 and this causes the material to be delivered rapidly through the huller.

One of the advantages of our device lies in the fact that the huller element is formed of a unitary element in which no obstructing angles or openings are included, so that any straw or other foreign material entering the feed-collar 12 will be delivered to the huller element and carried therethrough without winding or tangling. This is a very important point inasmuch as heretofore great difficulty has been experienced with various types of hullers in which the huller element clogs and causes a great deal of trouble and delay.

The helical plates 23 not only assist in advancing the material rearwardly in the huller casing, but also greatly assist in reinforcing and strengthening the plates 20. This is also very essential as it is necessary that the plates 20 be rigid and engage the grain without vibrating. The success of devices of this kind depends largely upon administering an abrupt and positive blow to the grain hulls, which causes them to open by the sudden strain imparted thereto.

It will therefore be seen that we have provided an oat huller of simple, durable and inexpensive construction, which is capable of rapid and positive hulling of large quantities of grain without tangling or clogging.

We claim as our invention:

1. An oat huller comprising a cylindrical casing having one end closed, said closed end being provided with a central opening having a rearwardly projecting collar, a hopper for delivering grain to said collar, said hopper having a bearing, a shaft rotatively mounted in said bearing and projecting centrally and longitudinally through said collar, a huller element rigidly secured to the rear end of said shaft and comprising a disk provided with radial blades having their inner ends adapted to rotate about said collar, the outer end of the back edge of each of said blades having a rearwardly projecting lug, and means for rotating said shaft.

2. An oat huller comprising a cylindrical casing having one end closed, said closed end being provided with a central opening having a rearwardly projecting collar, a hopper for delivering grain to said collar, said hopper having a bearing, a shaft rotatively mounted in said bearing and projecting centrally and longitudinally through said collar, a huller element rigidly secured to the rear end of said shaft and comprising a disk provided with radial blades having their inner ends adapted to rotate about said collar, the outer end of the back edge of each of said blades having a rearwardly projecting lug, the lower edge of each of said rearwardly projecting lugs being provided with a circumferential flange.

3. An oat huller comprising a cylindrical casing having one end closed, said closed end

being provided with a central opening having a rearwardly projecting collar, a hopper for delivering grain to said collar, said hopper having a bearing, a shaft rotatively mounted in said bearing and projecting centrally and longitudinally through said collar, a huller element rigidly secured to the rear end of said shaft and comprising a disk provided with radial blades having their inner ends adapted to rotate about said collar, the outer end of the back edge of each of said blades having a rearwardly projecting lug, the spaces between said radial blades having helical plates to support and strengthen said blades and also to advance material through said huller.

4. An oat huller comprising a cylindrical casing having one end closed, said closed end being provided with a central opening having a rearwardly projecting collar, a hopper for delivering grain to said collar, said hopper having a bearing, a shaft rotatively mounted in said bearing and projecting centrally and longitudinally through said collar, a huller element rigidly secured to the rear end of said shaft and comprising a disk provided with radial blades having their inner ends adapted to rotate about said collar, the outer end of the back edge of each of said blades having a rearwardly projecting lug, the spaces between said radial blades having helical plates to support and strengthen said blades and also to advance material through said huller, the forward edge of each of said blades being bent laterally and in a direction of the advance of said blades.

5. An oat huller comprising a casing, a shaft rotatively mounted therein, a huller element secured to said shaft, comprising a disk provided with radial blades, the outer end of the back edge of each blade having a rearwardly projecting lug, and a hopper for feeding grain to the inner ends of said blades.

6. An oat huller comprising a casing, a shaft rotatively mounted therein, a huller element secured to said shaft, comprising a disk provided with radial blades, the outer end of the back edge of each blade having a rearwardly projecting lug, a space between said radial blades having helical plates to support and strengthen said blades and also advance material through said huller, and a hopper for feeding grain to the inner ends of said blades.

7. An oat huller comprising a casing, a shaft rotatively mounted therein, a huller element secured to said shaft, comprising a disk provided with radial blades, a space between said radial blades having helical plates to support and strengthen said blades and also to advance material through said huller, and a hopper for feeding grain to the inner ends of said blades.

8. An oat huller comprising a casing, a

shaft rotatively mounted therein, a huller element secured to said shaft, comprising a disk provided with radial blades, the spaces between said radial blades having helical plates to support and strengthen said blades and to advance material through said huller, the forward edges of said blades being bent laterally and in the direction of the advance of said blades, and a hopper for feeding grain to the inner ends of said blades.
